UNITED STATES PATENT OFFICE

ZANVIL C. LOEBEL, OF SHOREWOOD, WISCONSIN, ASSIGNOR TO A. O. SMITH CORPORATION, OF MILWAUKEE, WISCONSIN, A CORPORATION OF NEW YORK

WINDOW CONSTRUCTION

Application filed January 16, 1931. Serial No. 509,134.

This invention relates to window construction and more particularly to means for securing window panes in place within a sash.

In the drawing wherein are illustrated several modifications of the present invention:

Fig. 1 is a view of a window frame having a glass pane secured therein;

Fig. 2 is a cross sectional view taken on the plane represented by the line 2-2 of Fig. 1; and

Figs. 3 and 4 are similar views of modified forms of construction.

Referring now more particularly to the drawing, the sash 10 is composed of a frame member 11 and a retaining strip 12, the latter being secured to the frame by means of the bolts 13. Disposed within the channel formed between the frame member 11 and retaining strip 12, is a thin aluminum strip 14 of U-shaped cross section. The U shaped strip 14 is spaced from the bottom of the channel in the sash by means of cork spacer blocks 15, two of which are ordinarily employed in each side of the frame.

Disposed within the channel shaped strip 14 is a pane of glass 16 which is spaced from the sides of the channel shaped strips by means of cork strips 17. The edge of the glass is spaced from the bottom of the channel shaped strips by means of resilient non-drying putty 18. The strip of putty 18 is formed by an extruding process in order that the same will be of uniform thickness along the entire sides of the frame.

The sides of the channel shaped strip 14 are provided with a plurality of spaced projections 19 for preventing relative movement between strips 14 and the cork strips 17. If desirable, the exposed edges of the cork strips 17 and U shaped strip 14 may be covered by means of a fillet 20 of putty positioned in the angle formed between the glass and the members 11 and 12 of the sash, to preclude the entrance of moisture thereto. The putty 20 is also of the resilient non-drying kind. However, since both the strips 14 and 17 are composed of non-erosive materials, the fillet 20 of putty need not be provided, since any

moisture which may enter the channel

formed in the frame would in no way cause deterioration of these strips.

In assembling the structure described, the retaining strips 12 are forced toward the frame member 11 to put the cork strips 17 under compression to form a tight joint between the glass and the frame and the retaining strips are then secured in this position to maintain the joint.

The construction above described allows for relative lateral movement between the frame member and the glass when the latter is subjected to lateral pressure and also allows for longitudinal movement of the glass with respect to the frame due to relative expansion between the glass and the frame. The structure is especially designed to accommodate this longitudinal movement between glass and aluminum which have a relatively great difference of thermal coefficients of expansion, but it is equally well adapted to any two substances having different coefficients of expansion. When, for example, a strong wind is blowing against the pane of glass, the glass will be forced in one direction and slightly further compress one of the cork strips 17, and also one of the putty fillets 20 on the leeward side of the glass. Upon abatement of this wind pressure upon the glass the putty and cork strips will resume their original shape.

During expansion or contraction of the frame and glass there will be relative longitudinal movement of the two only at the top and sides of the window. There will be no relative movement between the glass and the frame at the lower edge, since the weight of the glass always maintains the same seated within the channel shaped strip. The longitudinal movement of the glass within the frame at the top and sides of the frame may cause a separation of the glass from the putty fillets 20, but this separation would not allow any appreciable amount of water to enter in between the glass and the fillets at the sides and top of the window. Should water enter between the glass and fillets 20 it would be very difficult for it to pass from the channel to the other side of the glass. In order to positively preclude

any such possibility, resilient non-drying putty 22 may be interposed between the lower edge of the U shaped strip 14 and the bottom of the channel formed by the members

11 and 12 of the frame, and between the cork spacers 15 and portions of the strip 14 which are out of contact therefrom.

The construction shown in Fig. 3 differs from that shown in Fig. 2 in that the U shaped metal strip is in contact with the glass, and the cork strips are interposed between the metal strip and the members 11 and 12 of the frame. Relative movement between the cork strips and the U shaped metal strips is prevented in a manner similar to that described in connection with Fig. 2.

Fig. 4 differs from Fig. 1 in that it has additional cork strips 21 which are interposed between the sides of the U shaped metal strip and the members 11 and 12 of the frame.

Although the foregoing description is necessarily of a detailed character in order to completely set forth the preferred embodiments of the invention, it is to be understood that the specific terminology is not intended to be restrictive or confining and it is to be further understood that various rearrangements of parts and modifications of structural detail may be resorted to, without departing from the scope or spirit of the invention as herein claimed.

What is claimed and desired to be secured by Letters Patent is:

1. In window construction, a sash frame having a channel therein, a pane of glass having its edge portions disposed within said channel, cork strips interposed between the sides of said channel and said pane to permit relative lateral and longitudinal movement between said frame and said pane and means retained in position by the glass for precluding withdrawal of said cork strips from the channel during relative longitudinal movement of said frame and said pane.

2. In window construction, a sash frame having a channel therein, a pane of glass having its edge portions disposed within said channel, resilient spacing means between the bottom of said channel and the edges of said pane, cork strips interposed between the sides of said channel and said pane to permit relative lateral and longitudinal movement between said frame and said pane, and means retained in position by the glass for precluding withdrawal of said cork strips from the channel during relative longitudinal movement of said frame and said pane.

3. In window construction, a sash frame having a channel therein, a strip of U shaped cross-section disposed within said channel, a pane of glass having its edge portions disposed within said strip, resilient means disposed in the bottom of said strip for spacing said pane therefrom, and cork strips inter-

posed between the sides of said strip and said pane to permit relative lateral and longitudinal movement between said frame and said pane.

4. In window construction, a sash frame having a channel therein, a strip of U shaped cross-section disposed within said channel, resilient spacing blocks between the bottom of said channel and said strip, a pane of glass having its edge portions disposed within said strip, resilient means disposed in the bottom of said strip for spacing said pane therefrom, and cork strips interposed between the sides of said strip and said pane to permit relative lateral and longitudinal movement between said frame and said pane.

5. In window construction, a sash frame having a channel therein, a strip of U shaped cross-section disposed within said channel, a pane of glass having its edge portions disposed within said strip, resilient means disposed in the bottom of said strip for spacing said pane therefrom, cork strips interposed between the sides of said strip and said pane to permit relative lateral and longitudinal movement between said frame and said pane, and means for precluding withdrawal of said cork strips from the U shaped strip during relative longitudinal movement of said frame and said pane.

6. In window construction, a sash frame having a channel therein, a metallic strip of U shaped cross-section disposed within said channel, resilient spacing blocks interposed between the bottom of said channel and said strip, a pane of glass having its edge portions disposed within said strip, resilient means disposed in the bottom of said strip for spacing said pane therefrom, cork strips interposed between the sides of said strip and said pane to permit relative lateral and longitudinal movement between said frame and said pane, and means for precluding withdrawal of said cork strips from the U shaped strip during relative longitudinal movement of said frame and said pane.

7. In window construction, a sash frame having a channel therein, an aluminum strip of U shaped cross-section disposed within said channel, a pane of glass having its edge portions disposed within said aluminum strip, a strip of extruded resilient non-drying putty disposed in the bottom of said aluminum strip for spacing said pane therefrom, cork strips interposed between the sides of said aluminum strip and said pane to permit relative lateral and longitudinal movement between said frame and said pane, and means comprising projections on said aluminum strip for precluding withdrawal of said cork strips therefrom during relative longitudinal movement of said frame and said pane.

8. In window construction, a sash frame having a channel therein, a metal strip of

5 **U** shaped cross-section disposed within said channel, cork spacing blocks interposed between the bottom of said channel and said metal strip, a pane of glass having its edge portions disposed within said metal strip, a strip of extruded resilient non-drying putty disposed in the bottom of said metal strip for spacing said pane therefrom, cork strips interposed between the sides of said metal strip and said pane to permit relative lateral and longitudinal movement between said frame and said pane, and means comprising projections on said metal strip for precluding withdrawal of said cork strips from the **U** shaped strip during relative longitudinal movement of said frame and said pane.

9. In window construction, a sash frame having a channel therein, a metal strip of **U** shaped cross-section disposed within said channel, a pane of glass having its edge portions disposed within said strip, cork strips interposed between the sides of said metal strip and said pane and means comprising projections on said metal strip for precluding withdrawal of said cork strips from said **U** shaped metal strip during relative movement of said frame and said pane.

10. In window construction, a sash frame having a channel therein, a metal strip of **U** shaped cross-section disposed within said channel, a pane of glass having its edge portions disposed within said strip, and cork strips interposed between the sides of said channel and the sides of said metal strip to permit relative movement between said frame and said pane.

11. In window construction, a sash frame having a channel therein, a metal strip of **U** shaped cross-section disposed within said channel, a pane of glass having its edge portions disposed within said strip, cork strips interposed between the sides of said channel and the sides of said metal strip to permit relative movement between said frame and said pane, and means for precluding relative movement between said metal strip and said cork strip.

12. In window construction, a sash frame having a channel therein, a metal strip of **U** shaped cross-section disposed within said channel, a pane of glass having its edge portions disposed within said strip, and cork strips interposed between the sides of said metal strip and said pane and between the sides of the channel and the sides of the metal strip to permit relative movement between said frame and said pane.

13. In window construction, a sash frame having a channel therein, a metal strip of **U** shaped cross-section disposed within said channel, a pane of glass having its edge portions disposed within said strip, cork strips interposed between the sides of said metal strip and said pane and between the sides

of the channel and the sides of the metal strip to permit relative movement between said frame and said pane, and means for precluding relative movement between said metal strip and said cork strips.

14. In a window structure, a sash frame having a channel therein, a pane of glass having edge portions thereof disposed within said channel, a sheath resiliently mounted on the edge portion of the pane of glass permitting relative movement between the sheath and the glass, and resilient means in the bottom of the channel for receiving the sheath.

In witness whereof I have signed my name at Milwaukee, Wisconsin, this 10th day of January, 1931.

ZANVIL C. LOEBEL.
